CLAIM

We claim the ornamental design for a telephone, as shown and described.

DESCRIPTION

FIG. 1 is a front perspective view of a telephone showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines in the figures show portions of the telephone which form no part of the claimed design.

The unshaded surfaces within the solid circular receiver dock form no part of the claimed design.

The parts of the telephone shown between the symbolic break lines form no part of the claimed design.

1 Claim, 4 Drawing Sheets(56)
